UNITED STATES PATENT OFFICE

166,738

TOY DISK GUN

Robert W. Clauss, Riverdale, N. Y.

Application May 13, 1950, Serial No. 9,932

Term of patent 7 years

(Cl. D34—15)

To all whom it may concern:

Be it known that I, Robert W. Clauss, a citizen of the United States of America, residing at Riverdale, in the county of Bronx and State of New York, have invented a new, original, and ornamental Design for Toy Disk Gun, of which the following is a specification, reference being had to the accompanying drawing, forming part thereof.

Fig. 1 is a top view;

Fig. 2 is a side view;

Fig. 3 is a front view; and

Fig. 4 is a rear view of a toy disk gun showing my new design.

The matter shown in dotted lines is for illustrative purposes only.

I claim:

The ornamental design for a toy disk gun, substantially as shown and described.

ROBERT W. CLAUSS.
